ATTORNEY'S

UNITED STATES PATENT OFFICE.

BENJAMIN WOLF, OF PHILADELPHIA, PENNSYLVANIA, ASSIGNOR TO THE NATIONAL METAL EDGE BOX COMPANY, OF NEW JERSEY.

DESIGN FOR A MATCH SAFE OR TRAY.

SPECIFICATION forming part of Design No. 31,299, dated August 1, 1899.

Application filed February 13, 1899. Serial No. 705,444. Term of patent 7 years.

To all whom it may concern:

Be it known that I, BENJAMIN WOLF, a citizen of the United States, residing at Philadelphia, county of Philadelphia, and State of Pennsylvania, have invented and produced a new and original Design for Match Safes or Trays, of which the following is a full, clear, and exact description, reference being had to the accompanying drawings, which form a part of this specification.

My design can best be understood by referring to the accompanying drawings, of which—

Figure 1 is a perspective view looking at the top, and Fig. 2 a perspective view looking at the bottom, of a match safe or tray embodying my design.

A A are the two ends of the match safe or tray embodying my design, and B B the two sides.

A portion C of the bottom, in the shape of a right-angled triangle and at one of the cor-

ners of the box, is provided with a series of corrugations or serrations. The side of the triangle adjacent to the side B is considerably longer than the side adjacent to the end A. This triangular-shaped roughened portion C, its shape, and its location relative to one side and end of the tray constitute the essential features of my design.

D is a hole near one corner of the bottom of the tray.

Having now fully described my design, what I claim, and desire to protect by Letters Patent, is—

The design for a match safe or tray substantially as shown and described.

In testimony of which invention I have hereunto set my hand, at Philadelphia, on this 9th day of February, 1899.

BENJAMIN WOLF.
